UNITED STATES PATENT OFFICE.

FRANK A. CASTEEL, OF WASHINGTON, DISTRICT OF COLUMBIA, AND ROBERT M. MAYFIELD, OF KINGWOOD, WEST VIRGINIA.

MINER'S-LAMP-ATTACHMENT MEANS.

1,148,889.

Specification of Letters Patent.

Patented Aug. 3, 1915.

Application filed November 10, 1914. Serial No. 871,430.

To all whom it may concern:

Be it known that we, FRANK A. CASTEEL and ROBERT M. MAYFIELD, citizens of the United States, residing at Washington, District of Columbia, and Kingwood, Preston County, West Virginia, respectively, have invented certain new and useful Improvements in Miner's-Lamp-Attachment Means, of which the following is a specification.

10 The means usually employed for attaching miners' lamps to miners' hats or caps admits of the lamps having a play which is annoying and otherwise objectionable because of the jar occasioned by the swaying or lateral vibratory movement of the lamp resulting from the natural movements of the miner when at work.

This invention provides securing means for the miner's lamp which, while admitting 20 of the lamp being placed in position upon the hat or cap or removed therefrom with the greatest facility by the usual slip-joint, will at the same time prevent any play or movement of the lamp when attached to the 25 hat or cap, thereby avoiding the jar, inconvenience and other annoyance usually experienced by the ordinary joint which, permits of the lamp having a swaying movement and lateral play.

30 The invention consists of the novel and peculiar joint between the lamp and the bracket attached to the hat or cap, such joint admitting of placing the lamp in position or removing it from the cap in the ordinary 35 way but which joint will be free from any lateral play and hold the lamp rigid.

The invention also consists of the unique 40 form of bracket embodying a socket formed in such a manner as to coact with the lug of the lamp to preclude any possible swaying of the lamp when the latter is placed in position on the hat or cap.

The invention furthermore consists of the 45 novel features, details of construction and combinations of parts which hereinafter will be more particularly set forth, illustrated and claimed.

In the drawings hereto attached: Figure 1 is a view in elevation, parts being broken 50 away, of means for attaching a miner's lamp to a miner's hat or cap embodying the invention. Fig. 2 is a horizontal section of the lamp attaching means, the lamp being indicated in full lines. Fig. 3 is a perspective 55 view of the bracket as seen from the rear.

Fig. 4 is a perspective view of the upper portion of the bracket as seen from the front. Fig. 5 is a perspective view of a portion of a miner's lamp showing more clearly the lug attached thereto for coöperation with the socket of the bracket. Fig. 6 is a detail section of a modification.

Corresponding and like parts are referred to in the following description and indicated in all the views of the accompanying drawings by the same reference characters.

The bracket which is attached to the hat or cap comprises members 1, 2 and 3, corresponding respectively to the crown, body and vizor, or brim of the hat. This bracket 70 is preferably constructed of sheet material, such as metal, so as to be light and resilient. Opposite edge portions of the component parts of the bracket are reinforced, as indicated at 3^a, such reinforcements consisting of edge portions of the blank from which the bracket is formed being folded upon themselves. In the preferable construction the crown member 1 of the bracket is in a slightly lower plane than the upper edge 75 of the body member 2, thereby leaving a projecting portion 4 extending vertically above the forward portion of the part 1. The vertically extending portion 4 is formed by folding the blank upon itself and then bending the part 1 outwardly from the part 2.

80 a short distance from the folded edge, as indicated most clearly in Fig. 3. A socket 5 is formed in the upper portion of the vertical or crown part 2 of the bracket and is 85 adapted to receive the lug carried by the lamp. The socket 5 is transversely elongated, as shown most clearly in Fig. 2, and is comparatively narrow between its front and rear walls. The length of the socket 90 is such as to insure a firm and substantial connection being obtained between the co-operating parts, such as the socket and lug, comprising the joint. The body portion 2 95 of the bracket constitutes the front wall of the socket. The rear wall of the socket is formed by means of a strip of sheet material, such as metal, having its end portions secured between the part 2 of the bracket and the folded edge portions 3^a thereof. The strip is indicated at 6 and has its middle portion 7 deflected rearwardly so as to 100 form the space which constitutes the socket. It is noted that the front and rear walls of the socket are resilient, hence are adapted to 105 110

yield to admit of the lug being pressed into the socket so as to obtain a snug fit therein and prevent any possible play or movement. While it is contemplated to secure the strip 6 to the bracket in any manner, yet it is preferred to attach the same by means of the folded edge portions 3^a, thereby simplifying the construction and avoiding the necessity for utilizing extraneous fastening means. A vertically extending slot 8 is formed in the front wall of the socket and opens through the upper edge of the part 2, thereby admitting of the lamp being placed in position or removed from the socket by means of a slip-joint. The slot 8 is open at its upper end and the vertical walls defining such slot are flared at their upper ends, as indicated at 9, thereby giving a flare to the entrance end of the slot so as to direct the lug into the socket and slot when placing the lamp in position.

The lug attached to the lamp comprises a web 10 and a plate 11. The web 10 has a relative vertical arrangement and is of a width corresponding to the width of the slot 8 so as to fit such slot snugly. One edge of the web 10 is joined to the rear wall of the lamp 12. The opposite vertical edge of the web 10 has the plate 11 joined thereto, such plate projecting equidistant from opposite sides of the web 10, hence such web occupies a medial position. The plate 11 is designed to enter the socket 5 and fit the same snugly. The plate 11 by reason of its function may be designated as the socket-plate and its lower end projects below the web 10 and is made tapering, as indicated at 13, so as to readily enter the upper end of the socket 5. The thickness of the socket-plate 11 corresponds to the distance between the front and rear walls of the socket 5 to insure a snug fit between such plate and the walls of the socket, thereby preventing any possible play or movement of the lug when the lamp is in position upon the bracket.

The bracket may be attached to the hat or cap in any usual way and the lug provided upon the lamp may be of any construction. The socket 5 is open throughout its length and when the lamp is in position it is limited in its downward movement by the web 10 engaging the lower closed end of the slot 8. The lamp is placed in position or removed by the usual slip-joint. If desired the front and rear walls comprising the socket 5 may be pressed together so that when the lug is slipped into the socket the plate 11 will press such walls apart and as a result the inward tendency of the front and rear walls of the socket to come together will create sufficient friction on the socket-plate 11 to prevent any possible movement or displacement of the lamp.

In the modification shown in Fig. 6 the crown portion 1 of the bracket is in the plane

of the body portion, hence the receiving end of the socket 5 is in the plane of the crown portion of the bracket. The vertically extending portion 4 is adapted to engage the lower end of the socket-plate 11 and thereby direct such plate to the socket when moving the lamp laterally along the upper part of the bracket, such tapered end of the plate 11 dropping into the socket when registering therewith. It is to be understood that the invention may be applied to the various types of miners' lamps and hats or caps, hence when adapting the invention to a particular style of lamp or head covering, it is to be understood that various changes in the form, proportion and minor details of construction may be resorted to within the scope of the invention as claimed, without departing from the essential features thereof.

Having thus described the invention what is claimed as new is:—

1. Means for attaching a miner's lamp to a miner's hat or cap, the same comprising a member having a transversely elongated socket formed between two walls which are resilient to yield, one of such walls being formed with a relatively vertically extending slot which is open at its upper end, and a lug attached to the lamp and comprising a socket-plate and a web to enter and fit within the open-ended slot formed in the wall of the socket.

2. Means for attaching a miner's lamp to a miner's hat or cap, the same comprising a member having a relatively vertically extending socket which is transversely elongated and comparatively shallow between the opposing walls, one of such walls having a relatively vertically extending slot which is open at its upper end and made flaring, and a lug attached to the lamp and comprising a socket-plate made tapering at its lower end, and a centrally disposed web connecting the socket-plate with the lamp and adapted to snugly fit within the open-ended slot of the socket.

3. Means for attaching a miner's lamp to a miner's hat or cap, the same comprising a bracket, a strip having end portions attached to the edge portions of bracket and an intermediate portion deflected to form a socket, the bracket wall of the socket having an open-ended slot formed therein, and a lug attached to the lamp and comprising a socket-plate and a web.

4. Means for attaching a miner's lamp to a miner's hat or cap, the same comprising a bracket having opposing edge portions folded, a strip placed against the bracket and having its end portions confined between folded edge portions of the bracket, said strip having its middle portion deflected to form a socket, the bracket wall of the socket having an open-ended slot formed therein, and a lug attached to the lamp and

comprising a socket-plate and a centrally disposed web.

5. In means for attaching a miner's lamp to a miner's hat or cap, a bracket formed of a sheet metal blank having its edge portions folded to form reinforcements, such blank being bent to form crown, body and vizor members, and a strip having its end portions secured to the body member of the bracket by means of the folded edge portions of the blank, such strip having its middle portion deflected to form a socket, the front wall of such socket having a relatively vertically extending slot.

6. The herein described bracket to be attached to a miner's hat or cap, the same being formed of a sheet metal blank having opposed edge portions folded, and such blank being bent to form crown, body and vizor members, the crown-member being slightly lower than the upper edge of the

body member leaving a vertically extending portion which is formed by a fold of the blank, and a strip placed against the rear side of the body member and secured at its 25 ends thereto by means of the folded edge portions of the blank, such strip having its middle portion deflected to form a socket, and such socket having a relatively vertically extending slot formed in its front wall, 30 the upper end of such slot being open and flared.

In testimony whereof we affix our signatures in presence of two witnesses.
